SANITARY SEAT COVER AND DISPENSING
CABINET THEREFOR

Arvo E. Wiitala, Ashtabula, Ohio

Application December 17, 1936, Serial No. 116,414

1. Claim. (Cl. 312—60)

This invention relates to improvements in seat covers, particularly in covers for the seats of toilets or the like and also, to improvements in dispensing cabinets for such types of covers; and the invention together with its objects and advantages will be best understood from a study of the following description taken in connection with the accompanying drawings wherein:—

Figure 1 is a front elevational view illustrating a suggested relative location of the dispensing cabinet, hopper and flush tank.

Figure 2 is a vertical sectional view through the cabinet.

Figure 3 is a top plan view of the cabinet.

Figure 4 is a perspective view of a suspension rod.

Figure 5 is a vertical transverse sectional view through the cabinet.

Figure 6 is a fragmentary detail sectional view through the upper portion of the cabinet showing the manner of supporting one end of a rod within the cabinet.

Referring to the drawings by reference numerals it will be seen that in accordance with the present invention two cover members are to be employed for each proper covering of the toilet seat. The cover members will be complementary to one another, each being of a size, shape and dimension to cover approximately one half of the toilet seat.

In the drawings the toilet seat cover members are indicated generally by the reference numeral 5 and each consists of a sheet of destructible material such as for example, tissue paper or the like. Each cover member 5 has an edge contour corresponding substantially to the edge contour of substantially one-half of a conventional toilet seat. At one end thereof each cover member 5 is provided with an opening 6, while at the relatively opposite end thereof, which latter end will terminate at the front end of one half section of the toilet seat proper, there is provided a tongue extension 7.

The cover members 5 are stored in a dispensing receptacle 8 provided therefor.

The receptacle 8 in vertical cross section and in end elevation is of a shape corresponding substantially to the shape of each of the cover members 5, or in other words is of a shape corresponding substantially to the shape of one half of a conventional toilet seat.

Further, the dispensing cabinet 8 includes an inclined bottom wall 9, vertical front and rear walls 10, 11, a straight vertical side wall 12 and

a side wall 13 which latter conforms somewhat to the outer edge contour of a toilet seat.

The receptacle or container 8 is open at its top and for the top of the container or receptacle there is provided a suitably constructed removable top or cover member 14.

For supporting the respective opposite ends of a suspension rod 15, front wall 10 and rear wall 11 are respectively formed at their upper ends as at 16 and 17 respectively to present vertical 10 grooves opening at the top of the receptacle so that the member 15 trained through the openings 6 in the cover member 5 may be placed into the container or receptacle through the top thereof, and with the respective opposite ends of the rod 15 engaged in the grooves 16, 17 said rod will be supported at an incline and in a manner to suspend the cover member 5 within the receptacle.

The rod 15 being inclined toward the front 10 of the container or cabinet it will be apparent that the members 5 will have a tendency to slide toward the front 10 of the cabinet or receptacle to successively align with a slot 18 that extends from a point substantially midway of the top and bottom of the wall 13 of the cabinet downwardly 25 to and across bottom wall 9 to terminate at a point upwardly from the lower edge of wall 12. Through the provision of this slot the cover members 5 may be individually and successively removed from the cabinet or receptacle 8.

To facilitate the removal of each of the cover members 5 the front wall 10 is provided adjacent the bottom thereof with an opening 19 through which a finger may be passed to engage the extension 7 in a manner to exert a downward thrust 35 on a cover member 5 for forcing the lower end of the latter through the slot 18 where it may be grasped with the other hand of the user and pulled through the slot 18 to complete the removal of the cover member from the dispensing cabinet 40 or casing.

As suggested in Figures 2 and 5, the material from which the cover members 5 are formed may be relatively stiff, or treated with some material as to render these cover members stiff so that 45 the side edges thereof may be bent downwardly to provide side flanges 20 and to otherwise give the cover member the cross-sectional shape suggested in Figure 2. When so shaped and constructed it will be seen that each cover member 50 will, as it were, positively unite itself with its half of the toilet seat so as not to be easily displaced. However, where the cover members are so constructed cover members particularly designed for each of the two halves of a toilet seat would 55

be necessary. This would also require the use of two cabinets one cabinet for each type of seat cover.

However, this expense may be dispensed with 5 by having the cover members 5 flat throughout their entire dimensions so that they can be reversed to accommodate a selected half of the toilet seat cover.

It will be also understood that the dispensing 10 cabinet 8 is secured to the wall of the toilet-room preferably at one side of the flush tank 21 through the medium of fastening screws or the like 22. To accommodate these screws 22, the rear wall 11 is suitably apertured and is also 15 provided with an extension 11a that is apertured and provides an attaching flange through the medium of which and one of the screws 22 a positive securing of the cabinet in position on the wall can be effected.

20 It will also be noted, that in order to preclude misplacement of the cover 14 there is provided for the latter an anchoring chain or other flexible element c that is anchored at one end to the wall 12 and at a relatively opposite end to the 25 lid or cover 14.

Also to close the upper end of the slot 17 the lid or cover 14 is provided with a tongue or extension 14a as clearly shown in Figures 2 and 3.

Also in forming the openings 6 in cover members 30 5 struck-out tongues 6a are provided and which are folded downwardly against the inner faces of the cover members to cooperate with

the tongues 7 for uniformly spacing the cover members on the rods 15 as clearly shown in Figure 2.

It is thought that a clear understanding of the construction, utility and advantages of an invention of this character will be had without a more detailed description.

Having thus described the invention, what is claimed as new is:—

In an apparatus of the character described, a 10 dispensing container comprising a bottom wall disposed at an angle to the horizontal, side and end walls rising from said bottom wall, one of said side walls being curved outwardly toward the top to provide an increase in width at the top 15 of the container to accommodate a plurality of segmental seat covers conformably fitted in the container, a removable cover member for the top of said container, said container being provided with internal grooves at the upper ends of the 20 end walls of the container, a suspension rod having its respective opposite ends arranged in said grooves and from which the seat covers are suspended and said container being provided with a slotted opening extending entirely across the 25 bottom adjacent its lowermost portion, said slotted opening also extending upwardly from the bottom of each of the side walls into the increased width of the upper portion of the container to facilitate removal of the wider end of 30 the seat cover through the opening.

ARVO E. WIITALA.
